UNITED STATES PATENT OFFICE.

AMINDO RENZETTI AND LUIGI RENZETTI, OF NEW YORK, N. Y.

LEAF-FOLDING MECHANISM FOR TABLES.

1,151,394.

Specification of Letters Patent. Patented Aug. 24, 1915.

Application filed May 20, 1914. Serial No. 839,764.

To all whom it may concern:

Be it known that we, AMINDO RENZETTI and LUIGI RENZETTI, both subjects of the King of Italy, and residents of the city of 5 New York, borough of Manhattan, county and State of New York, have invented a new and Improved Leaf-Folding Mechanism for Tables, of which the following is a full, clear, and exact description.

10 This invention relates to improvements in tables, and particularly to means for folding the extra leaves provided therefor.

The object in view is to provide an improved mechanism for unfolding and again 15 folding the extra leaves of the table when the permanent parts of the table are moved back and forth in an opening and closing movement.

Another object of the invention is to provide 20 an improved mechanism for quickly raising and opening extra leaves of a table when the table is pulled apart.

A still further object of the invention is 25 the provision of an improved folding mechanism for a plurality of leaves which will cause the leaves to unfold from beneath the table when the table is separated the first time, and which will cause the leaves to fold to a position beneath the top of the 30 table when the table is opened a second time, this mechanism also providing for an automatic centering whether one or more are used.

In carrying out the objects of the invention 35 a top of any desired kind is provided which is associated with suitable slides of any desired form, as for instance the usual variety of slides for tables. Associated with the center slide is a pedestal of substantially the usual 40 structure, which pedestal is not separable, while the top is separable. Arranged on this pedestal and beneath the top is a frame for receiving one or more extra leaves as may be desired, together with operating mechanism, 45 whereby the leaves may be raised and opened and again closed and lowered. This mechanism is partially carried by the leaves but part is connected with the top of the table so that the two parts of the top of the table 50 when moved will cause a proper operation of the mechanism which in turn will move the leaves as desired, either from a folded to an unfolded position or from an unfolded to a folded position.

55 In the accompanying drawings—Figure 1 is a bottom plan view of a table with an em-

bodiment of the invention applied thereto, a pair of leaves being shown inserted into the top; Fig. 2 is a fragmentary bottom plan view of the structure shown in Fig. 1, 60 one half of the top being pulled to one side; Fig. 3 is a bottom plan view of the structure shown in Fig. 1 with one half of the table pulled to one side for its full distance, the leaf being folded; Fig. 4 is a fragmentary top plan view of the table shown in Fig. 1, the same disclosing only that part of the table shown in Fig. 2; Fig. 5 is a sectional view through Fig. 7 approximately 65 on line 5—5, the same being shown on an enlarged scale; Fig. 6 is a section through Fig. 4 on line 6—6, the same being shown on an enlarged scale; Fig. 7 is a view similar to Fig. 4 except that the leaves are in a folded position; Fig. 8 is a bottom plan 70 view of approximately half of the table in a closed position with all of the leaves in a folded position; Fig. 9 is an enlarged detailed fragmentary perspective view of one of the leaves and the operating mechanism 75 therefor; Fig. 10 is an enlarged fragmentary sectional view through Fig. 9 approximately on line 10—10; Fig. 11 is a bottom plan view of a pair of cams embodying certain features of the invention.

Referring to the accompanying drawings by numeral, 1 indicates a pedestal of any desired kind provided with a top 2 divided into parts or sections 3 and 4. These sections may be of any desired kind, and when 80 in contact present a circular top. Section 3 is rigidly connected to slide 5, while section 4 is rigidly connected to slide 6, slides 5 and 6 being in turn slidably connected with fixed slides 7 and 8. Slides 7 and 8 are rigidly secured to cross bars 9 and 10, which cross bars are rigidly secured to the pedestal 1. Rigidly secured by any desired means to the cross bars 9 and 10 are filling blocks 11 and 12, and also a frame 13. Frame 13 is 85 constructed according to Patent No. 1,096,732, designed to accommodate leaves 14 and 15 when the arms are in a folded position. The frame 13 is cut away somewhat for accommodating the hinges 16 and 17, and associated parts as more clearly 90 shown in Figs. 5 and 6.

Arranged upon each leaf are a plurality of means which open or unfold the leaves, and also which close or fold the leaves. 110 These means do not act on the leaves during their entire opening and closing move-

ment, but act sufficiently long to allow the momentum to finish the opening and closing operation. On the stationary part of the table are arranged co-acting means which cause a proper actuation of the mechanism on the leaves. In Fig. 9 will be seen the mechanism on one of the leaves, and as the mechanism on each of the leaves is alike the description of this mechanism will 5 equally apply to the mechanism on the other leaves. It is to be understood that the leaf shown in Fig. 9 is inverted. The leaf 14 is provided with a body or central portion 18 and side members 19 and 20, the side members 19 and 20 being connected with the body 18 by the hinges 16' and 17', which hinges may be of any desired construction. The hinges 16 and 17 are of special construction, and each comprises a plate 21 to 10 which is rigidly secured an arm 22. Also an arm 23 is pivotally connected to plate 21 by a suitable pivotal pin 24, arm 23 being provided with a lug or shoulder 25 for limiting the swinging movement of the arm in 15 one direction, whereby when the arm is raised the same will move plate 21 together with the respective side members 19 and 20. The respective arms 23 are adapted to be engaged by the crank members 26 and 27. 20 pivotally mounted in suitable supports connected with the body 18. The crank members 26 and 27 have pivotally connected therewith links 28 and 29, which links in turn are pivotally connected to sliding plates 25 30 and 31 through suitable upstanding members 32 and 33 and pintles arranged therein. The plates 30 and 31 are provided with lower portions 34 and 35, respectively, arranged to slide between the guides 36 and 37, which guides are rigidly secured to the portion 18 of the leaf 14. The ends of guide 30 are bent so as to extend normal to said guide, and thus present stops 38 and 39 for limiting the movement of the plates 30 and 40 31. It is to be noted that plates 30 and 31 are provided with projections 40 and 41 which accommodate springs 42 and 43. Springs 42 and 43 are connected to the arms 22 of the respective hinge members 16 and 45 17 through suitable connecting means, as for instance chains 44 and 45. Retractile springs 46 and 47 are connected at one end to the body 18 and at the other to the portions 34 and 35 whereby slides 30 and 31 50 are given a continual tendency to move toward the stops 38 and 39. The lower portions 34 and 35 may be connected with the plates 30 and 31 in any desired manner, as for instance by rivets, and are provided 55 with upstanding members or stops 48 and 49 which are designed to snap into notches 50 and 51 formed in the sliding catch 52. The sliding catch 52 is provided with an offset portion 53 whereby the end in which 60 the notches 50 and 51 are arranged is above

plates 30 and 31, and in addition an abutment is provided for the spring 54 (Fig. 10) which spring has one end pressing against wall 55 in the notch 56 of the body 18. The end of the sliding plate 52 opposite the end having notches 50 and 51 is offset for providing a raised stop 58. The body of the catch 52 is held properly in position by a plate 58 secured to the leaf 14 by any desired means, said body sliding in a groove 59 formed in the leaf 15, as clearly shown in Fig. 10. It is to be noted that the springs 42 and 43 are slack when the leaf 14 is unfolded, but are brought under tension when the leaves are folded. This tension is not 65 very great, and is intended to cushion to a certain extent the closing action caused by springs 46 and 47 forcing arms 23 against plate 21.

In operation when it is desired to insert an extra leaf in the table while the parts are in the position shown in Fig. 8 all that is necessary is to pull against section 3. When the pulling action has caused section 3 to move to the position shown in Fig. 9 70 springs 42 and 43 will be brought under a considerable tension which will cause end members 19 and 20 to quickly move to the position shown in Fig. 3. As the section 3 begins to move from the position shown in Fig. 8 to that shown in Figs. 4 and 7 the pins 60 will be disconnected from section 3 and also the swinging bars 61 and 62 will be moved somewhat toward each other. This movement is continued until the bars 100 61 and 62 have pressed the upstanding members 48 and 49 into the notches 50 and 51. It is to be understood that the bars 61 and 62 are arranged to engage upstanding members 48 and 49 when the section 3 is moved 105 to an open position. The bars are pivotally mounted on the stationary block 12 and are adapted to engage a switch structure 63 (Fig. 11) for causing a back and forth movement of the bar. The switch structure 110 63 is formed with converging guides 64 and 65 and reversely positioned converging guides 66 and 67 which at their widest portion fit against the narrowest portion of the ways 64 and 65. Spring pressed switches 115 68 and 69 are arranged on ways 66 and 67 so that the bars 61 and 62 cannot spread when the section 3 is moved back until the bars have escaped from the ways 66 and 67, the entire switch structure 63 being connected 120 with section 3. It is of course understood that a similar structure is connected with section 4 so that both sides of the table operate similarly. Connected with the bars 61 and 62 are springs 70 and 71 which tend 125 continually to separate the bars when released from switch 63. In order to prevent too great a separation a retaining keeper 72 is provided which is rigidly secured to the frame or casing 13. After the parts have 130

been moved to the position shown in Fig. 4 section 3 is moved back (or closed) until the same is contacting with the leaf 14, and is also moved until leaf 14 presses against the 5 section 4 which is moved preferably for the distance of half the width of the leaf when only one leaf is being used, whereby the inserted leaf will be arranged centrally of the table.

10 When it is desired to retire the leaf the section 3 is pulled outwardly to its fullest extent so that pins 60 may be disengaged from sections 3 and 4, whereupon springs 42 and 43 will quickly fold ends 19 and 20. 15 The sections 3 and 4 are then forced toward each other until they meet in the center, whereupon the top is closed. If it is desired to again use leaf 14, section 3 is moved from the position shown in Fig. 8 to the 20 position shown in Fig. 2. It will be noted that the catch 52 is in engagement with the projection 73 when the parts are in the position shown in Fig. 8. When the section 3 is moved to the position shown in Fig. 2 projection 73 is disengaged from catch 52 and 25 also the pivotally mounted bars 61 and 62 are brought together which will cause the stops 48 and 49 to engage the notches 50 and 51 which will bring the various springs under tension. As springs 42 and 43 hold the leaf open and springs 46 and 47 are held 30 against movement the tension of these springs is desirable at this time. After the parts have been moved as just described section 3 is forced back until pins 60 engage 35 suitable apertures in section 3 as shown in Fig. 1. When the section 3 is again pulled to an open position as shown in Fig. 7, the pins 74 on the ends of the leaf are moved 40 by the slides 5 so that the leaf will be disengaged from both sections and also so that catch 52 may engage projection 73 in order to 45 release the stops 48 and 49, and consequently springs 46 and 47 and associated parts which causes a folding action of the leaf. The section 3 is then closed as heretofore described.

It is to be noted that section 3 is moved out of contact with the leaf 14, and then leaf 50 14 is moved out of contact with section 5. This is caused by pin 74 operating in slot 75, slot 75 being in the slide 5, while pin 74 is arranged in the leaf 14. As soon as the alining pins 60 of the leaf 14 are disengaged 55 both from the section 3 and from section 4 or the next adjacent inserted leaf, the springs 46 and 47 will cause the leaf to fold and move into the box or frame 13. The springs just mentioned cause the folding action 60 and the leaf automatically falls by gravity into the box, suitable guides being provided for guiding the movement of the leaf into the box or frame 13, and out of the box or frame 13, the same forming no part 65 of the present invention as such structure is

claimed in applicant's former patent heretofore mentioned. By this construction and arrangement either of the leaves may be automatically unfolded and again folded by movement of either section of the top, and if 70 desired by a movement of both sections of the top both leaves may be folded and unfolded.

It is to be noted that each leaf and the various mechanisms shown in Fig. 9 are not 75 in any way secured to the table or to the box or frame 13, and the only connection between the leaf and the mechanism carried thereby to the table are the pins 60 and the bars 61 and 62. This allows either of the 80 leaves to be bodily removed manually whenever desired without affecting any of the parts, and without the use of any tools. The projection 73 as shown in Fig. 6 is part of a swinging stop plate 76 which is divided at 85 77, and is provided with a clamping screw 78 operating a suitable slot whereby the projection 73 may be adjusted to correspond to the height of the catch 52.

What we claim is—

1. In a device of the character described, the combination with a table having the top divided into sections and a foldable leaf normally positioned below said top, of means for raising said leaf and unfolding 95 the same when said sections are separated, said means comprising a pair of pivotally mounted members, springs connected with said members, a sliding member connected with each of said springs for bringing the 100 same under tension, means connected with the parts of said top for causing said slides to be moved against the action of said springs whereby the springs are brought under tension, and a switch mechanism on 105 one of said sections for actuating said last mentioned means.

2. In a device of the character described, the combination with a table having a separable top, said top being divided into sections and a foldable leaf arranged normally beneath said top, of means for unfolding and raising said leaf when said top is separated, and for folding and lowering said leaf when not desired, said means comprising 115 springs connected with the outer ends of said leaf for raising the leaf and opening the same, a sliding member connected with each of said springs for bringing the same under tension, means connected with the 120 parts of said top for causing said slides to be moved against the action of said springs whereby the springs are brought under tension, a switch mechanism on one of said sections for actuating said last mentioned 125 means, a pivotally mounted member acting on the outer ends of said leaves for folding the same, a rod connected with said pivotally mounted member and with said slides for transmitting motion from said slides to said 130

pivotaly mounted members, a spring connected with said slides, said spring being brought under tension by the movement of said slides toward each other, a catch for engaging said slides when moved toward each other and holding the same against movement, and means for engaging said catch for releasing the same, whereby the slides will move under the action of said last mentioned springs, and will operate the parts connected therewith for folding said leaf.

3. In a device of the character described, the combination with a table having a top 15 divided into two parts, said parts being movable, and a plurality of folding leaves normally arranged beneath said top but adapted to be moved in the same plane as said top for forming a continuous surface, 20 of means for actuating said leaves for causing the same to be folded and unfolded, said means comprising a pivotally mounted arm connected with the folding parts of each of said leaves, an arm rigidly connected with 25 the folding parts of each of said leaves, a spring for each of said last mentioned arms, a pivotally mounted member for each of said pivotally mounted arms for actuating the same, a link connected with each of said 30 pivotally mounted means, a sliding plate connected with said link and with said spring, a second spring for each of said plates for holding the same in a predetermined position and returning the same to 35 that position when moved therefrom, means for bringing said springs under tension, said means moving said plates, a catch for holding said plates against movement after the springs have been brought under tension, 40 and a projection adapted to release said catch when the movable parts of said top are forced away from each other, whereby said last mentioned spring will move said pivotal members and fold said leaves.

45. 4. In a device of the character described, the combination with a table having a divided top, the sections of which are movable, and a foldable extra leaf normally arranged beneath said top, said foldable extra leaf being formed with a central body and hinged end members, of means for folding and unfolding said leaf and causing the leaf to be moved to the same plane as said top, and to a plane beneath said top, said 50 means comprising a pair of springs connected with said hinged end members for unfolding said end members, a pivotally mounted arm connected with each of said end members for folding the same, a pivotally mounted member for actuating said arms, a spring for each of said pivotally mounted members, a link connecting one end of said spring with said pivotally mounted members, means for holding said last mentioned springs under tension when said end 55

members are in an unfolded position, a member for releasing said means when one of said sections is pulled away from the other, whereby said leaf will be moved to a folded position, and means for bringing the 70 first mentioned spring under tension previous to the separation of said sections, whereby upon a complete separation of said sections said first mentioned springs will move said hinge members to an open position.

5. In a device of the character described, the combination with a table provided with a top divided into sections which may be separated for insertion of an extra leaf, and 80 a foldable extra leaf normally arranged beneath said top, of means for substantially simultaneously unfolding said leaf and raising the same to the top and simultaneously folding and lowering said leaf, said means 85 comprising a pair of springs for folding said leaf, a pair of springs for opening said leaf, means arranged in said top for releasing one pair of springs whereby the leaf will be folded by one pair of said springs, and 90 means actuated by said top for bringing the other pair of springs under tension whereby the same is adapted to unfold said leaf when said sections are moved apart.

6. In a device of the character described, 95 a table provided with a top divided into sections, said sections being slidable, and a foldable extra leaf arranged normally beneath said top, said foldable extra leaf being formed with a central body and foldable 100 ends, of means for unfolding said ends and raising the entire leaf to the same plane as said top, and also folding said leaf so that the same may move down by gravity beneath said top, said means comprising a 105 spring for each of said ends for folding said leaf, a spring for each of said ends for unfolding said leaf, a sliding plate connected to each pair of springs, a catch engaging said plates for holding the same against 110 movement after said springs have been brought under tension, means arranged in the path of movement of said catch for releasing the same when said top is separated, whereby said leaf will be moved to a folded 115 position, and means actuated by said top for bringing said springs under tension when the top is closed and the leaf has been folded.

7. In a device of the character described, 120 the combination with a table having a top formed in separable sections, and a folding leaf having a central body and a pair of end hinged members, of means for folding and unfolding said leaf, said means comprising an extension secured to each of said hinged 125 members, a retractile spring connected with each of said extensions, a sliding plate connected with each of said springs, a catch for locking said sliding plate against movement after the springs have been 130

brought under tension, a pivotally mounted arm connected to each of said hinged ends, each of said arms being provided with a stop for engaging the ends for moving a pre-determined distance, a swinging member for engaging said arms and moving the same so as to close said hinged ends, a link connected at one end to the respective swinging members, the opposite end of each of said links being connected with said sliding plates, a pair of retractile springs connected to said plates for moving the same away from said catch when the catch is released, said last mentioned springs acting as power means for closing said hinged ends, means arranged on the stationary part of the table engaging said catch for releasing the same when the leaf has been moved so as to be disengaged from the top, whereby said last mentioned springs will fold said leaf, and means for bringing both of said springs under tension and said plates into engagement with said catch when said top is brought to a closed position, whereby when said top is again opened said first mentioned spring will act on said hinged ends for opening the same.

In testimony whereof we have signed our names to this specification in the presence of two subscribing witnesses.
